F. M. SLATER.
AIR FEED CONTROL FOR ROCK DRILLS.
APPLICATION FILED JULY 23, 1920.

1,407,591.

Patented Feb. 21, 1922

UNITED STATES PATENT OFFICE.

FRED M. SLATER, OF EASTON, PENNSYLVANIA, ASSIGNOR TO INGERSOLL-RAND COMPANY, OF NEW YORK, N. Y., A CORPORATION OF NEW JERSEY.

AIR-FEED CONTROL FOR ROCK DRILLS.

1,407,591.

Specification of Letters Patent. Patented Feb. 21, 1922.

Application filed July 23, 1920. Serial No. 398,387.

To all whom it may concern:

Be it known that I, FRED M. SLATER, a citizen of the United States, residing at Easton, in the county of Northampton and 5 State of Pennsylvania, have invented certain new and useful Improvements in Air-Feed Control for Rock Drills, of which the following is a specification.

This invention relates to fluid pressure 10 operated rock drills of the hammer type, but more particularly to air feed control for the feeding element of a stope drill.

The operator wishes to maintain full rotation and hammer power with reduced air 15 feed when going through a soft spot for instance, but with the usual air feed controlling device, he must take his hand off the rotation handle provided on the machine, and turn the throttle, and he may not do this 20 quickly enough to avoid trouble.

The primary object of the present invention is to enable the operator to control the feeding element or air feed cylinder directly from the drill handle without removing 25 his hand. The control may be effected by a simple pressure of the fingers, or preferably by the thumb according to the type of handle provided. The air feed may thus be substantially instantaneously controlled 30 and dropped when required or restored to full air feed in a simple manner.

Further objects of the invention will hereinafter appear and to all of these ends the invention consists of the devices and features of construction shown in the accompanying drawings, in which—

Figure 1 is a side elevation partly in vertical section of a stope drill embodying the invention,

40 Figure 2 is an enlarged detailed side elevation of a portion of the handle, and

Figure 3 is a horizontal sectional view through the handle on the line 3—3 of Figure 2 looking in the direction of the arrows.

45 Referring to the drawings, a stope drill is illustrated in Figure 1 having the usual cylinder A and front head B carrying the drill steel C. The front head is connected to the cylinder as by means of the usual side bolts D. The cylinder A and its operative parts comprise the percussive element of the tool for imparting the impact blows of the piston hammer to the drill steel. The drill steel may be rotated by any suitable means, 50 in this instance a machine of the independ-

ent rotation type being illustrated having the rotation motor casing E formed in the back end portion of the machine.

The feeding element comprises the usual air feed cylinder F having the piston G and 60 the piston rod H provided with the rock engaging point J. Between the back end portion E and the air feed cylinder F is located the head block K and the cylinder A, back end portion E, head block K and air feed 65 cylinder F are held together as by means of the through bolts L. Motive fluid is admitted to the percussive and feeding elements of the machine through the inlet O controlled by the throttle P in the head 70 block K. The head block is provided with a rotation handle P' for the machine, although the handle could be connected as desired to any suitable portion of the casing. In this instance, the handle P' is provided 75 with the downward extension Q forming a convenient portion to be grasped by the hand of the operator.

In accordance with my invention instead of controlling the air feed in the usual manner, as by means of the throttle P, I provide 80 a valve R in the handle controlling ports and passages leading to the feeding element, thereby enabling the operator to regulate the feeding element in accordance with the 85 requirements of the work without removing his hand from the handle.

In this instance, the handle is preferably hollow provided with the passage S extending from a port T at the inner end of the 90 handle to a valve chamber U near the handle extension Q. The valve chamber U communicates with the atmosphere through the end of the handle by means of the port V and the chamber is closed by means of the 95 screw threaded plug W between which and the valve R a spring X is compressed so that the valve R normally closes the atmospheric port V. The valve is preferably provided with an operating button Y at its end 100 forming a convenient device for manipulation by the thumb Z of the operator.

The handle P' is preferably removably connected to the head block K in this instance the inner end of the handle being 105 provided with a tapered portion a having a reduced neck b through which the port T opens. When the handle is held in position in the head block K as by means of the nut c communication is afforded from the air 110

feed cylinder F through the passage d to the space around the reduced neck b and from thence through the passage S in the handle to the valve chamber U.

5 The device is simple and enables the operator to efficiently and substantially instantaneously control the air feed under all circumstances without taking his hand from the operating handle.

10 I claim:

1. A rock drill having a percussive element and a fluid pressure feeding element, a rotation handle rigidly secured to the machine and adapted to be grasped and held by 15 the operator, and a valve located near the outer end of said handle controlling ports and passages leading from the feeding element, thereby enabling the operator to reduce the pressure in the feeding element in 20 accordance with the requirements of the work, without removing his hand from the handle.

2. A rock drill having a percussive element and a fluid pressure feeding element, a 25 hollow rotation handle rigidly secured to the machine and communicating with the feed-

ing element and the atmosphere, said handle being adapted to be grasped and held by the hand of the operator, and a valve located near the outer end of said handle for reducing the pressure in the feeding element, thereby enabling the operator to regulate the feeding element in accordance with the requirements of the work without removing his hand from the handle. 30 35

3. A rock drill having a percussive element and a fluid pressure feeding element, a hollow rotation handle removably and rigidly connected to the drill casing and communicating with the feeding element and the atmosphere, said handle being adapted to be grasped and held by the operator, and a valve located near the outer end of said handle controlling an exhaust port from the said feeding element, whereby the pressure in the feeding element may be reduced substantially instantaneously in accordance with the requirements of the work. 40 45

In testimony whereof I have signed this specification.

FRED M. SLATER.
